DESIGN FOR A SERVING TABLE

Harold A. Treitel, New York, N. Y., assignor to Treitel-Gratz Company, Inc., New York, N. Y., a corporation of New York

Application November 29, 1943, Serial No. 111,809

Term of patent 7 years

(Cl. D33—14)

To all whom it may concern:

Be it known that I, Harold A. Treitel, a citizen of the United States, residing at New York, in the county of New York and State of New York, have invented a new, original, and ornamental Design for a Serving Table, of which the following is a specification, reference being had to the accompanying drawing, forming part thereof.

The figure is a perspective view of the serving table, showing my new design.

I claim:

The ornamental design for a serving table,
substantially as shown.
